UNITED STATES PATENT OFFICE.

MADISON L. CHRISTIAN, OF CLINTON, IOWA, ASSIGNOR TO THE AMERICAN WIRE FABRIC COMPANY, OF CLINTON, IOWA, A CORPORATION OF IOWA.

LOOM.

1,055,259.

Specification of Letters Patent.

Patented Mar. 4, 1913.

Application filed August 9, 1910. Serial No. 576,297.

To all whom it may concern:

Be it known that I, MADISON L. CHRISTIAN, a citizen of the United States, residing at Clinton, in the county of Clinton and 5 State of Iowa, have invented new and useful Improvements in Looms, of which the following is a specification.

The present invention has reference to looms, and more especially to improvements 10 in or relating to the shuttles and the operating or carrying mechanism associated therewith.

The invention is designed primarily for application to looms for weaving wire cloth 15 and to looms of the type specified wherein two separate pieces of cloth are woven at one time.

A structural embodiment of the invention is illustrated in the accompanying 20 drawings, wherein:

Figure 1 is a front elevation of the improved loom. Fig. 2 is a vertical sectional view of the same. Fig. 3 is an enlarged detail sectional view of the socket members 25 and the releasing devices which coöperate with the same.

It is the purpose of this invention, as above stated, to provide a loom construction wherein provision is made for weaving two 30 separate pieces of cloth at once. In consequence, two separate shuttles designated by the reference numerals 1 and 2 are employed, which shuttles are carried backward and forward through the corresponding 35 sheds a and a' by a pair of bars 3 and 4. These bars have a reciprocatory movement imparted thereto through the medium of suitable operating mechanism A which is preferably of the type shown and described 40 in the patent granted to myself and Elmer E. Reynolds, No. 809776, dated January 9, 1906. Reference may be had to this patent for a complete description of said mechanism, it being only necessary, so far as the 45 present invention is concerned, to state that the respective inward and outward movements of the bars take place simultaneously. During their movements, the said bars are guided by means of looped vertical straps 50 b and b' , arranged in pairs at the ends of the horizontal cross-pieces b^2 and b^3 carried by the uprights b^4 which form a portion of the loom frame B and are mounted upon the horizontal side beams b^5 of the latter, said 55 cross-pieces constituting the supplemental

frame B'. The heddles a^2 and a^3 which raise and lower the sheds a and a' are themselves actuated in the usual manner by suitable mechanism C operatively connected with the drive shaft 5, said actuating mechanism requiring no specific description, since it is of conventional type. 60

At the center of the supplemental frame B' is located a support 6, preferably constituted by a trough-shaped plate having 65 its upper and lower edges fastened to the adjacent cross-pieces b^2 and b^3 . To the inner face of the front portion of this support there is secured a pair of sockets 7 and 8, each of which has arranged therein a 70 clamping device designed to engage the outer end of the adjacent shuttle. These clamps, the operating mechanism therefor, and the sockets wherein they are disposed, constitute the essential features of the invention, the preferred form of clamp comprising 75 a member which is movable in one direction to engage the shuttle and in the other direction to release the same.

Referring to Figs. 1 and 3, it will be seen 80 that the shuttles are provided at opposite ends with catches 9 and 10, the front catches 9 being designed to project into the sockets, and the rear catches 10 to project into the front ends of the hollow bars 3 and 4. The 85 clamps, which engage the first-named catches, are shown in the present construction as in the form of oscillatory or rocking rods 11 and 12 disposed in longitudinal openings 13 in the thickened lower portions 90 of the sockets. These rods are provided at their outer ends with fingers 14 and 15, while their inner ends have attached thereto arms 16 and 17 pivotally connected to the upper ends of vertical rods 18 and 19, the 95 lower ends of the latter rods being pivoted in turn to the front ends of a pair of substantially horizontal rods 20 and 21. Rods 20 and 21 are pivoted at their rear ends to a bracket 22, fastened to a cross-piece 23 supported in the loom frame in any suitable manner, and are rocked or vibrated by a pair of cams 24 and 25 mounted on shaft 5. The cams are so timed that one of the horizontal rods will be swung upwardly while the other descends, carrying with them the rods 18 and 19, which, in turn, operate the rockers 11 and 12. Consequently, during this operation, the finger on one rocker will be moved into engagement with the catch 100 105 110

on one shuttle, while the finger on the other rocker will be simultaneously disengaged from the catch on the other shuttle, or, in other words, one shuttle will be clamped in its socket and the other shuttle released, the outer ends of said sockets having the lower portions thereof cut away to permit the requisite movement of the fingers.

Mechanism of a somewhat similar nature 10 is also provided for clamping and unclamping the shuttles in the shuttle bars; but since this mechanism forms no essential feature of the invention, no description thereof is necessary, beyond the fact that it may include, as shown, a rocker 26 for each bar, 15 provided at one end with a finger 27 arranged to engage the rear catch 10 on the corresponding shuttle, and at the other end with a lug 28 which is adapted to be engaged and turned by a lug 29 provided upon 20 the front end of a horizontal rod 30, this rod being reciprocated by a rocking lever 31 pivoted to the frame of the loom and operated in any suitable manner from the 25 drive shaft. The action of the secondary rockers 26 is the same as that described with reference to the main rockers 11 and 12, one of the said secondary rockers being caused to disengage a shuttle when the 30 other shuttle is engaged by the other rocker, the corresponding main rockers being, respectively, engaged and disengaged with and from the front catches of the shuttles at the same time.

35 The operation may be stated as follows, reference being had to Fig. 1, wherein the left-hand shuttle 2 is shown as clamped in the socket 8, and the right-hand shuttle 1 is shown as clamped to the shuttle bar 3, the 40 bars having almost reached the limit of their outward movement. When said bars reach the support 6 on their succeeding inward movement, the catch end 9 of shuttle 1 will be projected into socket 7, and the 45 catch end 10 of shuttle 2 will be projected into the adjacent end of bar 4. At this time, the main and secondary clamping and releasing mechanisms will be actuated, where-

upon the main rocker 11 in socket 7 will be caused to engage catch 9 of shuttle 1, and 50 the other main rocker 12 will be caused to disengage catch 10 of shuttle 2, while the secondary rocker 26 of bar 3 will be turned so as to disengage catch 10 of shuttle 1, and the corresponding rocker 26 of bar 4 55 will be engaged with catch 10 of shuttle 2. The last-named shuttle will thus be released from socket 8 and clamped to bar 4, while the first-named shuttle will be clamped in socket 8 and released from bar 3. The bars 60 will then start on their outward movement, the heddles being alternately raised and lowered at the proper times in order to permit the passage of the shuttles through the sheds, as will be understood. It will be 65 seen, therefore, that during each inward movement of the bars, one bar will carry a shuttle inwardly through its shed, and deposit said shuttle in its socket, while the other bar is empty, and on each outward 70 movement of said bars, the shuttle just deposited in its socket will remain therein and the previously deposited shuttle will be carried away from the support and caused to travel outwardly through its shed, this cycle 75 of operations being continued until the weaving of the cloth is completed.

I claim as my invention:

In a loom, the combination of a support; 80 a pair of shuttles; mechanism for moving said shuttles into and out of the support; a pair of rocking clamps mounted in said support and arranged to engage said shuttles when the latter are in place therein; and mechanism for simultaneously rocking one 85 clamp into position to engage one shuttle and for rocking the other clamp into position to release the other shuttle.

In testimony whereof I have hereunto set my hand in presence of two subscribing witnesses.

MADISON L. CHRISTIAN.
